BELT

Filed Sept. 29, 1948

UNITED STATES PATENT OFFICE

2,659,895

BELT

Jack Horowitz, Brooklyn, N. Y.

Application September 29, 1948, Serial No. 51,800

3 Claims. (Cl. 2—322)

1

The present invention relates to belts or similar supporting articles to be worn by ladies as well as by gentlemen.

It is one of the objects of the present invention to provide means affording inexpensive manufacture of belt or like articles from flexible metallic mesh which are aesthetic in appearance and of durable construction and are not subject to tear.

It is a further object of the invention to provide means facilitating a belt structure which is only flexible in a direction transversely to the length of the belt and therefore readily conforms to the shape of the body of the wearer.

It is a still further object of the present invention to provide means yieldably and elastically connecting the belt ends which may be brought into engagement with each other by means of a buckle with tongue or a buckle with clamping member without any change of the belt body proper.

Still another object of the invention is to provide means permitting the employment of one or more spring elements connected to the buckle, said spring elements being pivotally supported by securing means serving to maintain in position the loop of the belt end in which said buckle is retained.

Yet another object of the present invention is to provide means affording expansion of the belt in lengthwise direction thereof by means of springs and/or by means of spaced apart engageable stop means.

A still further object of the present invention is to provide means for hiding from view the aforesaid spring elements accommodated within the belt loop holding or retaining the buckle.

With the above and other objects in view, the invention will be hereinafter more particularly described and the combination and arrangement of parts will be shown in the accompanying drawings and pointed out in the claims which form part of the specification.

In the drawing:

Fig. 1 is a fragmentary rear elevational view of the engaged ends of a belt by means of a buckle and made in accordance with the invention, a part of the belt ends being broken away.

Fig. 2 is a cross-section taken along line 2—2 of Fig. 1.

Fig. 3 is a fragmentary rear elevational view similar to that of Fig. 1 with a different buckle applied to the belt ends.

Fig. 4 is a cross-section taken along line 4—4 of Fig. 3.

2

Fig. 5 is an enlarged cross-section taken along line 5—5 of Fig. 1.

Fig. 6 is an enlarged detail shown in section and depicted in Fig. 4.

Referring now more particularly to the drawing, there is disclosed in Figs. 1 and 2 a two-ply metallic wire mesh strip or body 10, which has a front wall 11 and flaps 12, 13 bent over at 12a, 13a to form the rear wall 14 of the belt (Fig. 5). Edges 15, 16 of flaps 12, 13 abut against each other without being fixedly joined together and form an open seam 17. Front wall 11 and rear wall 14 are held together adjacent end 18 of the belt 10 by means of a plurality of grummets or eyelets 20 which are equidistantly spaced from each other, as seen in Figs. 1 and 3.

The opposite end 19 of the belt 10 forms a loop 21, which is fixed in position by means of one or more suitable rivets 22 (one rivet being shown for clarity's sake).

This belt structure may be used for various purposes, such as for wear by ladies or men and to this end, any suitable buckle may be selected for releasably coupling loop end 21 to belt end 18.

In the embodiment illustrated in Figs. 1 and 2 a frame-shaped buckle 25 provided with a movable element in the form of a tongue 24 is employed, the tongue 24 being pivotally supported on frame bar 23 of said buckle. Tongue or movable element 24 arranged on buckle bar or portion 23 may have any suitable length and is adapted to extend through one of the eyelets 20 for engagement therewith and for joining the ends of the belt.

Mounted on rivet 22 of loop 21 and concealed by said loop 21 is a yoke-shaped member 26 which is provided with suitable elongated bores 27 of various lengths for accommodating therein respective ends 28 of coil spring elements 30, 31, 32, 33 whose opposite ends 29 are anchored on buckle bar or portion 23a.

Since frame bars 23b, 23c extend above and below folded outer edges 12a, 13a buckle 25 is free to move in longitudinal direction of the belt under tension of said spring elements 30 to 33, which may be subject to stretching strains or extension commensurate with varying components of produced tension during wear of the belt. Yoke 26 which rides on rivet 22 but is suitably secured thereon may swing about said rivet to follow various stretching strains as may be easily realized (see arrow C).

In order to conceal loop 21 of belt end 19 from view, further to accommodate extension 18a of belt end 18 and to maintain the outer end 34 of

loop 21 in place sleeve member 35 is employed which encases belt end 19 and may be coupled as by hinge means (not shown) with buckle 25 proper.

It is to be noted that the sleeve member 35, as illustrated in Figs. 1 and 2, is affixed to the bar 23a by means of suitable spacer pins 35a, 35b. The sleeve is preferably of a length to keep the loop 21 and the parts 26 to 33 contained within said loop in place.

Fig. 2 is a cross-section of belt 10 in simplified form (not shown as a two-ply structure for sake of clarity).

Figs. 3, 4 and 6 show belt 10 of identical shape and appearance as that of Figs. 1 and 2, but with a different buckle applied thereto.

Buckle 40 extends with its rear flaps 41, 42 over the edges 12a, 13a of the belt walls 11, 12-13 and carries a tongue or clamping member 45 in suitable bearings 43, 44 formed by said flap pin 46. This tongue or clamping member has a curved end 50 with corrugations 47 for a purpose later referred to. From cam-shaped or curved end 50 of clamp member 45 extends a loop-shaped frame 48 terminating in a cross-bar 49 to which springs 30 to 33 are attached in a manner similar to that described in regard to bar 23a of Fig. 1.

It will be easily recognized from Fig. 6 that corrugation 47 does not engage directly the rear face of belt 10 but comes to lie rearwardly of one of the eyelets 20 against which the extremity of curved end 50 abuts and from which is spaced a successive or adjacent eyelet 20, whereby belt 10 (in addition to the elasticity produced by the aforesaid spring means 30-33) has a certain give which is predetermined by the selected distance between successive adjacent eyelets 20. Thus, belt end 18 may be moved between successive eyelets 20 according to arrows A for the purpose of adjusting the belt, corrugations 47 impeding movement of the belt end beyond said eyelets 20 when clamping member or tongue element 45 with curved end 50 is swung with pivot 46 to engagement or locking position (Figs. 4 and 6).

It will be further noted that front wall 11 of belt end 18 will be maintained in spaced relation from inner wall 40a of buckle 40 by the aforesaid adjacent eyelets 20 so that the outer belt surface will always be protected from wear and attack by the metal parts of the buckle.

The protective sleeve or cover 35, referred to in regard to Figs. 1 and 2, has been omitted in Fig. 3 for clarity's sake.

Swinging movement of clamp 45 in the direction of arrow B will release curved end 50 from engagement with eyelet 20, whereby belt end 18 may be further adjusted (by bringing eyelet 20 into abutting engagement with the extremity of curved end 50) or disengaged from buckle 40.

It ensues from the above description that one and the same belt structure made of fine metallic wire mesh and equipped with suitable spaced eyelets may be employed for a lady's belt (Figs. 1 and 2) as well as for a gentleman's belt (Figs. 3 and 4) without changing the body of the belt 10 proper.

It can thus be seen that there has been provided according to the invention a belt or similar article of support which comprises a body of flexible, fine metallic wire mesh, said body including a front wall having opposite longitudinal portions, which are folded over rearwardly of said front wall to thereby form the rear wall of said

belt, spaced-apart offset grummets forming stops and positioned adjacent one end of said belt, a buckle provided with an element hinged thereon, a loop arranged at the other belt end to which the buckle is attached, the buckle being provided with an element hinged thereon, securing means passing through said loop to close the latter and to retain a portion of said buckle within said loop, said hinged element being engageable with one of said grummets to thereby connect both said ends of said belt together, and means forming an extension of said buckle to substantially enclose said loop.

Having thus described the invention, what is claimed as new and desired to be secured by Letters Patent is:

1. A belt and similar article of support comprising an elongated body of flexible fine metallic wire mesh, said body including a front wall having a rear face and opposite longitudinal edges, rear wall flaps extending from said longitudinal edges rearwardly of said front wall and overlying the rear face of said front wall, spaced apart grummets positioned adjacent one end of said body and connecting said rear wall flaps with said front wall, a buckle provided with a tongue element, means on said buckle hingedly connecting said tongue element to said buckle, a loop arranged at the other end of said body and passing around a portion of said buckle, rivet means passing through said loop to close the same, said tongue element being engageable with one of said grummets to close said belt, yoke means pivotally engaging said rivet means, and spring means attached to and extending from said yoke means to said portion of said buckle for anchorage on the latter and on said yoke means.

2. A belt and like article of support comprising a body made of a single piece of flexible fine metallic wire mesh, said body including a front wall having a rear face and opposite longitudinal edges, rear wall portions extending from said longitudinal edges of said front wall and overlying the rear face of said front wall, spaced apart grummets positioned adjacent one end of said belt and connecting said rear wall portions with said front wall, a buckle having two spaced bars adjacent one end thereof, one of said bars being provided with an element hinged thereto, a loop arranged at the other belt end and connecting said buckle to said end, securing means passing through said loop to close the latter and to retain the other bar of said buckle within said loop, a yoke member pivotally engaged within said loop by said securing means, spring means extending from said yoke member to said other bar and anchored on the latter and on said yoke member, said hinged element being engageable with one of said grummets for connecting both said ends of said belt together, and sleeve means joined to said buckle on said other bar for concealing said loop.

3. A belt and like article of support comprising an elongated body having opposite ends connectable with each other, spaced apart grummets passing through said body and positioned adjacent one of said ends, a buckle having two spaced apart bars adjacent one end thereof, one of said bars being provided with a tongue element hinged thereto, a loop integral with and arranged at the other end of said body, a rivet arranged with respect to the longitudinal center line of said body and passing through said loop, the other bar of said buckle being retained within said loop, said tongue element being engageable with one

of said grummets to thereby connect both said ends of said body together, spring means contained within said loop, a yoke member pivotally connected to said rivet, said spring means being anchored on said other bar and extending therefrom for anchorage to said yoke members, to thereby permit yieldable movement of said buckle relative to said yoke member, and a sleeve member connected to said buckle adjacent said other bar and extending over said loop to conceal the same.
